UNITED STATES PATENT OFFICE.

GEORGE H. ZOUCK, OF ORANGE, NEW JERSEY, ASSIGNOR TO FRANKLIN RAILWAY SUPPLY COMPANY, A CORPORATION OF DELAWARE.

EXHAUST AND SEPARATOR SYSTEM FOR LOCOMOTIVES.

Application filed April 23, 1925. Serial No. 25,199.

My invention relates to exhaust and separator systems for locomotives and the like, and is particularly adaptable to taking care of the exhaust from intermittently operated auxiliaries, such as boosters especially where such exhaust is discharged in association with the main engine exhaust as in the co-pending application of Messrs. Peters and Vincent, Serial Number 625,710, filed March 10 17th, 1923. I aim to provide for separating and discharging liquid (water or oil) from the exhaust without complications or difficulties when the exhaust is discharged into the locomotive smoke-box.

How this and other objects and advantages can be realized through my invention will appear from my description hereinafter of a selected and preferred embodiment.

In the drawings, Fig. 1 is a fragmentary side view of a locomotive and booster, illustrating the application of the invention thereto.

Fig. 2 shows a vertical section through the separator shown in Fig. 1, on a larger scale.

Fig. 3 is a fragmentary view, showing a section through the valve shown in Fig. 2 and the associated parts, on a still larger scale than Fig. 2.

Fig. 4 shows a bottom view of the valve, with the casting in section as indicated by the line 4—4 in Fig. 3.

Fig. 1 shows a locomotive with an exhaust line 5 from an auxiliary, such as booster 6, discharging into the smoke-box 7—suitable flexible connections 8 being shown in the line 5 to accommodate the movement of the booster with the trailer truck 9, on which it is shown mounted. In the present instance, the exhaust line 5 is connected to the main locomotive exhaust nozzle 10, so that the auxiliary exhaust may assist in drafting the locomotive. Adjacent the smoke-box 7, a steam separator 11 is connected in the exhaust line 5, to extract entrained liquid (oil or water) from the auxiliary exhaust. This separator 11 is located at the low point of the line 5, so that the line may drain into it from both sides. The separator 11 is here shown as of a familiar commercial helico-centrifugal type, comprising a chamber 12 with an inlet 13 at one side and an inwardly projecting outlet 14 directly opposite at the other side. A helical baffle 15

in the inlet 13 throws any liquid in the steam against the sides of the chamber 12, and such liquid drains down and accumulates in the bottom of the chamber 12, whence it is discharged through an opening 16 and a pipe 17. In the present instance, the opening 16 is in a bushing 18, which serves as a seat for a cupped disc valve 19, pivoted on a pin 20 that extends through the walls of the valve chamber 21. This valve 19 is counterweighted at 22 to close automatically.

When the booster 6 is in operation, and exhaust steam is therefore passing through the line 5, the pressure of this steam combined with the weight of liquid accumulating in the bottom of the chamber 12 opens the valve 19, so that the liquid may drain off. When, on the other hand, the exhaust through the line 5 is cut off, the draft of the locomotive makes itself felt through the pipe 5 to lower the pressure in the separator chamber 12, so that the valve 19 is held fast to its seat 18 by the external air pressure. Thus influx of air through the separator 11 into the smoke box 7 is prevented and burning of the gases in the smoke box by such air is rendered impossible and, furthermore, interference with or reduction in the draft can not take place.

When neither the booster 6 nor the main locomotive is in operation, the valve 19 is free to open under the weight of any water draining into the chamber 12, so as to permit its discharge and keep the system clear.

I claim:—

1. The combination with a locomotive smoke-box and the main engine exhaust means discharging thereinto, of an auxiliary exhaust line, a separator in the exhaust line with a discharge for the separated liquid, and means for preventing draft of air through the separator into the smoke-box by the locomotive.
2. The combination with a locomotive smoke-box and the main engine exhaust means discharging thereinto, of an auxiliary exhaust line, a separator in the exhaust line with discharge for the separated liquid, and means for closing said discharge against influx of air under the locomotive draft while permitting free discharge of liquid.
3. The combination with a locomotive

smoke-box and the main engine exhaust means discharging thereinto, of an auxiliary exhaust line, a separator in the exhaust line with a discharge for the separated liquid, and an automatic valve for said discharge balanced to close against influx of air under the locomotive draft when the auxiliary ex-

haust is cut off, but to permit discharge of accumulating liquid during passage of the said auxiliary exhaust through the separator. ¹⁰

In testimony whereof, I have hereunto signed my name.

GEORGE H. ZOUCK.
